UNITED STATES PATENT OFFICE.

WILLIAM M. MCKAY, OF WILMOT, MICHIGAN.

STUMP-PULLER.

SPECIFICATION forming part of Letters Patent No. 352,765, dated November 16, 1886.

Application filed June 1, 1886. Serial No. 203,787. (No model.)

To all whom it may concern:

Be it known that I, WILLIAM M. MCKAY, a citizen of the United States, and a resident of Wilmot, in the county of Tuscola and State of Michigan, have invented certain new and useful Improvements in Stump-Pullers; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view showing my 15 improved stump-puller attached to a stump. Fig. 2 is a top view of the same as it would appear if stretched out upon the ground, and Fig. 3 is a detail view of the lower end of one of the legs.

20 Like letters of reference indicate like parts in the three figures.

My invention has relation to stump-pullers; and it consists in the improved construction and combination of parts, as will be hereinafter fully described and claimed.

25 Referring to the accompanying drawings, A represents two wooden poles used as uprights, the upper ends of which are formed at an angle to the main part of the poles, and have bolt-holes cut through them; B, an iron rod, having an eye formed at its upper end and a hook at its lower end; C, a draft-rod provided at its lower end with means for attaching a team to it, and at its upper end with curved 30 strips of iron D, secured to the sides thereof, and provided at their outer ends with bolt-holes; E, a bolt for securing together the poles, the iron rod, and the draft-rod, the iron rod being secured by its eye end between the 35 poles, and the poles between the ends of the strips D, which strips give to the draft-rod a bifurcated upper end.

The poles have an increasing taper from their crooked upper ends to their lower ends, which are made convex to allow them to rock 45 on their foundation during the pulling-operation, and which have recesses F formed in the center of the convex surface. (See Fig. 3.)

If the ground is soft, a boat, G, with a spur, H, in its center, is placed under the end of 50 each pole and staked to the ground, to prevent its slipping as the top of the apparatus is pulled over, the spurs at the same time preventing the poles from slipping on said boats.

In pulling a stump the poles are set astride 55 and a little to one side of the stump, opposite to the portion to be hitched to, and a chain attached to said portion and to the hook of the iron rod, Fig. 1. A team is then attached to the draft-rod, and in the first part of the pull 60 a lifting strain is exerted upon the stump. Then after the poles pass the vertical position the stump is pulled over onto its side.

Having thus fully described my invention, I claim and desire to secure by Letters Patent 65 of the United States—

In a stump-puller, the combination of two uprights, a connecting-bolt passing through their tops, a hook and chain suspended from the bolt, and a draft-rod, the lower end of 70 which is provided with means for attaching a team to it, and having curved strips secured to its upper end, the outer ends of said strips being mounted upon the connecting-bolt.

In testimony that I claim the foregoing as 75 my own I have hereunto affixed my signature in presence of two witnesses.

WILLIAM M. MCKAY.

Witnesses:

W. L. DOYLE,
PATRICK DELANEY.
